VARIABLE ATTENUATOR WITH LINEAR DRIVE

Stanley A. Johnson, New York, N. Y., assignor to
 Polytechnic Institute of Brooklyn, Brooklyn,
 N. Y., a corporation of New York

Application December 4, 1946, Serial No. 714,117

9 Claims. (Cl. 178—44)

1

This invention relates to variable attenuators for wave guides, and it is especially concerned with attenuators of the guillotine type in which a loss-producing plate-like element is inserted into the wave guide through a longitudinal slot formed in the broad side of the guide.

In wave guide attenuators of this type, the amount of attenuation normally increases exponentially with the amount of plate insertion into the guide. This is an undesirable characteristic, since the attenuation scale at the larger attenuation values becomes crowded.

One object of the present invention is to devise a drive arrangement for the attenuator plate whereby the attenuation scale is spread out and rendered substantially linear over its major working portion.

A further object of the invention is to devise a novel arrangement for mounting the attenuator plate for movement into and out of the slot in the wave guide.

A further object is to provide means for preventing loss of wave energy through the slot in the wave guide.

The preferred form of the invention is illustrated in the accompanying drawing in which

Figure 1 is a plan view of the variable attenuator;

Figure 2 is a side elevational view of Figure 1 with one cover plate removed and certain parts shown in section;

Figure 3 is a graph of two curves illustrating the operating characteristic of the attenuator; and

Figure 4 is a graph of curves illustrating the effect of the chokes provided adjacent the attenuator slot.

Referring to Figures 1 and 2 of the drawing, 1 indicates a short section of rectangular wave guide having a male coupling element 2 secured at one end and a female coupling 3 mounted on the other end. The male coupling 2 has its front end section 2a threaded for engagement with a female coupling on a section of wave guide to which it is to be coupled, and the rear portion 2b of the coupling is formed as a nut section. The female coupling element 3 is internally threaded in the end section 3a while the other end section 3b is formed as a nut section. This coupling element is free to rotate about the wave guide 1 and serves to clamp a circular head 1a rigidly secured to the end of guide 1 against the end of a male coupling element mounted on the adjacent section of wave guide to be coupled to the attenuator. The male coupling element 2 is

provided with a pair of forwardly extending lugs 2c which extend into similarly located slots formed in the peripheral edge of the head 1a of the female coupling on the adjacent wave guide section. These lugs maintain proper alignment between the coupled wave guide sections.

As shown in Figure 2, the mounting frame and casing for the attenuator is formed of an inverted U-shaped frame 4 positioned on the top broad face of the wave guide 1, and a bar-shaped member 5 arranged below the wave guide. Members 4 and 5 are of the same width as the guide 1, and a pair of cover plates 6 and 7 are secured on opposite sides of these frame members 4 and 5 to form an enclosed metallic housing in the space within the member 4 above the wave guide.

Mounted within the attenuator housing is a movable block 8 which carries an attenuator plate 9, the lower edge of which is rounded as shown at 9a. This attenuator plate is preferably formed of a relatively thin plate of dielectric material such as glass, and carries on one face thereof a thin metallic film which will produce an energy loss without introducing substantial resonant effects in the wave guide. The metallic film is preferably deposited by thermal evaporation in accordance with the process disclosed in copending application Serial No. 699,546, filed September 26, 1946. It will be obvious, however, that any other form of loss-producing plate-like element may be employed instead of that just described. The attenuator plate 9 is preferably mounted in the block 8 by means of a slot formed in the block and the upper edge portion of the plate is cemented into the slot.

The block 8 is mounted within the attenuator casing to have translational movement having both longitudinal and vertical components of motion simultaneously, and this is accomplished by a pair of pivoted links 10a, 10b and a spring 11. The two links 10a and 10b are short bars having V-shaped grooves formed in their ends which engage round roller bearing elements 10' and 10" mounted respectively on the frame member 4 and on the block 8. The tension spring 11 is connected between the block 8 and the frame 4, the spring being arranged to urge the block 8 in a direction such that the rollers 10" maintain constant contact with the lower ends of links 10a and 10b, and the upper ends of these links maintain constant contact with the rollers 10'. With this type of mounting, the links 10a will swing as if they were pivoted about the centers of pins 10' and 10", and the block 8 will remain parallel with the wave guide 1 in all positions.

2

Furthermore, the action of spring 11 tends to move the block 8 to the right in all positions of the block against the end of an adjusting screw 12 having threaded engagement with the right end of frame member 4 and having an adjusting knob 13.

At the other end of the attenuator casing is mounted a micrometer 14 which may be calibrated in units of attenuation such as decibels. The micrometer 14 is preferably mounted to respond to the longitudinal movement of the block 8, and for this purpose the mounting stem 14a extends through a hole in the left leg of the frame member 4 and is clamped in position by a set screw 15. The operating plunger 14b of the micrometer bears against the left end of the block 8.

With the construction as illustrated in Figure 2, the block 8 is constantly urged into contact with the end of adjusting screw 12, and the block is shown in Figure 2 in the position of maximum attenuation, or in the position of maximum insertion of the plate 9 into the wave guide. As the screw 12 is advanced into the attenuator casing, the block 8 is moved to the left and, due to the pivotal mounting of the links 10a and 10b, the block will also have a vertical component of movement resulting in the outward movement of the attenuator plate from the wave guide. Starting from the position of maximum attenuation as shown in Figure 2, the vertical component of movement is small by comparison with the horizontal component, but the ratio of vertical to horizontal movement increases as the screw 12 is advanced further into the attenuator casing. By arranging the micrometer 14 to respond to the horizontal movement alone, a near-linear relation is obtained between the movement of the screw 12 and the amount of attenuation introduced into the wave guide. Curve A in Figure 3 illustrates the relation between the horizontal movement of the block 8 (dial readings of micrometer 14) and the attenuation in decibels. As will be seen, this curve is a substantially straight line over the major portion of its length. Curve B in Figure 3 is a typical curve showing the standing wave ratio for different positions of attenuator adjustment.

From the foregoing it will be seen that the attenuator plate is mounted for translational movement within the slot in the wave guide in such manner that the plate has both horizontal and vertical components of movement simultaneously. The arrangement is such that the attenuator plate is constrained to move in the arc of a circle defined by a pivoted arm or link which in the position of maximum attenuation is substantially at right angles to the wave guide. Two parallel links are used in order to maintain the block 8 parallel with the wave guide 1 in all positions, but it is obvious that only one pivoted link is necessary if other means is employed to maintain the block parallel to the wave guide.

It has been found that the portion of the attenuator plate 9 extending outside of the wave guide acts as an antenna for launching waves into the attenuator casing from the wave guide, and this shunts energy from the wave guide, thus limiting the maximum attenuation obtainable to the attenuation of the shunt path. For the purpose of preventing this shunting of energy from the wave guide, a pair of magnetic chokes are mounted on each side of the attenuator plate adjacent the slot in the wave guide. These chokes are formed of bars 16 of suitable magnetic

material arranged on opposite sides of plate 9 and mounted upon a slotted plate 17 which is soldered or otherwise secured to the top face of the wave guide 1. Plate 17 serves to prevent longitudinal movement of the attenuator casing. Preferably, these choke bars are formed of "Polyiron" consisting of fine iron particles held together by a suitable binder.

The curves in Figure 4 illustrate the operation of the wave attenuator with and without chokes. Curve C shows the operation without the magnetic chokes and curve D shows the operation with the chokes. As will be seen, greater attenuation is obtained with the chokes and the curve is more linear.

For the purpose of illustration, the dimensions will be given of a variable attenuator suitable for use in the wave-band of 1.225 cm. to 1.275 cm. with a maximum attenuation of 40 decibels. The wave guide for this band measures $\frac{1}{2}$ inch by $\frac{1}{4}$ inch by 0.040 inch (wall thickness). The attenuation plate 9 is formed of "Pyrex" glass 0.038 inch thick, and the metal film on the plate has a resistance of 100 ohms per square. The plate has a length of 2 inches and a maximum width of 0.6 inch. The radius of curvature of the lower edge of the plate is $2\frac{1}{2}$ inches. The parallel link mounting for the block 8 permitted horizontal travel of 0.200 inch with a corresponding vertical travel of 0.170 inch.

The slot through which the attenuator plate enters the wave guide is $\frac{1}{8}$ inch wide, and the "Polyiron" strips were spaced 0.012 inch from the respective sides of the plate. The insertion loss of the complete unit is less than 0.3 db and the input VSWR is less than 1.12 for all attenuation settings within the band. The attenuation change between the band edge frequencies is below 1.5 db.

While a specific example has been given for a particular band of waves, it is obvious that the invention may be applied to other wave bands if desired.

The rounded lower edge of plate 9 serves to match the input impedance of the attenuator with the characteristic impedance of the wave guide, thus preventing noticeable wave reflection.

The parallel links 10a and 10b serve to guide the movement of the plate 9 in the wave guide along the arc of a circle, with the result that the rate of insertion of the plate into the guide varies over the range of movement of the plate. The ratio of the vertical component of movement to the longitudinal component decreases as the insertion increases, so that there is substantially a straight line relation between the attenuation and the longitudinal component of movement over the major portion of the range. This establishes substantially a straight line relation between the attenuation and the dial readings of micrometer 14 or the movement of adjusting screw 12.

The term "translational movement" has reference to motion in which all the points of the moving body have at any instant the same velocity and direction of motion.

We claim:

1. An attenuator for a wave guide adapted to convey electromagnetic wave energy having a slot formed longitudinally therein, a loss-producing plate-like element mounted for movement in said slot, and means for guiding said plate element for movement in said slot comprising a pair of parallel links pivoted at one end to a fixed support spaced from said wave guide on the

slotted side thereof and pivotally connected at the other end to spaced points on said plate element.

2. An attenuator according to claim 1 and including an indicator and means for actuating said indicator by the component of movement of said plate element longitudinally of said wave guide.

3. An attenuator according to claim 1 wherein said parallel links are enclosed within a metallic housing surrounding said slot, and including a pair of choke elements mounted on opposite sides of said slot closely adjacent the faces of said plate element.

4. An attenuator according to claim 1 and including a spring element acting on said plate-like element tending to move said plate-like element in one direction, and an adjusting screw mounted with its axis parallel with the axis of said waveguide and arranged to move said plate-like element in the opposite direction.

5. An attenuator for a waveguide having a slot formed longitudinally in one wall thereof comprising a loss-producing, plate-like element, means for mounting said element for movement into said slot comprising an elongated bar to which said plate element is attached, a pair of parallel links pivotally attached to said bar at spaced points thereon and having pivotal connections at their opposite ends with a fixed support at spaced points thereon, said bar being parallel with said waveguide, spring means interposed between said bar and said fixed support and tending normally to move said bar longitudinally in one direction, and an adjusting screw having threaded engagement with said fixed support with its axis parallel with said waveguide and arranged to impart longitudinal movement to said bar in the opposite direction.

6. An attenuator according to claim 5 and including an indicator mounted to respond to the longitudinal movement of said bar.

7. An attenuator for a wave guide having a slot formed longitudinally therein, a loss-producing plate-like element positioned within said slot, a movable adjusting member mounted for movement in a direction parallel with the axis of said wave guide and arranged to effect longitudinal movement of said plate-like element in said slot, and means controlled by the longitudinal movement of said plate-like element to impart movement of said plate element transversely of said wave guide and thereby to vary the extent of insertion of said plate-like element into said slot, the transverse component of movement being so related to the longitudinal component as to establish substantially a linear relation between the longitudinal movement of said adjusting member and the attenuation produced by said plate-like element.

8. An attenuator for a waveguide adapted to convey electromagnetic wave energy comprising, a section of waveguide having a slot formed longitudinally in one wall thereof, a loss-producing plate-like element mounted for movement through said slot, means for guiding said plate element through said slot with translational movement having a component of movement parallel with the longitudinal axis of said section and a component of movement directed transversely of said section, the ratio of said longitudinal component to said transverse component increasing progressively as said plate moves from a position of minimum insertion to a position of maximum insertion into said section, an attenuation indicator, and means for actuating said indicator in accordance with the longitudinal component of movement of said plate element.

9. An attenuator for a waveguide adapted to convey electromagnetic wave energy comprising, a section of waveguide having a slot formed longitudinally in one wall thereof, a loss-producing plate-like element mounted for movement through said slot, and means for guiding said plate into said slot with translational movement wherein all points of said plate travel along circular arcs of equal radii and having their centers of movement spaced from said waveguide on the slotted side thereof.
